UNITED STATES PATENT OFFICE.

JOHN E. JOHNSON, OF ELGIN, ILLINOIS, ASSIGNOR TO ILLINOIS WATCH CASE COMPANY, OF ELGIN, ILLINOIS, A CORPORATION OF ILLINOIS.

DESIGN FOR A PENDANT-STEM FOR WATCHES.

41,782.

Specification for Design.

Patented Sept. 19, 1911.

Application filed April 10, 1911. Serial No. 620,264. Term of patent 7 years.

To all whom it may concern:

Be it known that I, JOHN E. JOHNSON, a citizen of the United States, residing at Elgin, in the county of Kane and State of Illinois, have invented a new, original, and ornamental Design for Pendant-Stems for Watches, of which the following is a specification, reference being had to the accompanying drawing, forming part thereof.

In the drawing—Figure 1 is a side elevation of my pendant stem for watches, and

Fig. 2 is a plan view of my pendant stem, showing the bow arranged at right angles to the position shown in Fig. 1.

I claim:

The ornamental design for a pendant stem for watches as shown.

JOHN E. JOHNSON.

Witnesses:

THOMAS F. SHERIDAN,
HENRY A. PARKS.
